UNITED STATES PATENT OFFICE.

JAY F. LAWRENCE, OF CHICAGO, ILLINOIS.

HYDROCARBON-BURNER.

1,396,854.

Specification of Letters Patent. Patented Nov. 15, 1921.

Application filed October 26, 1918. Serial No. 259,776.

To all whom it may concern:

Be it known that I, JAY F. LAWRENCE, a citizen of the United States, and a resident of the city of Chicago, in the county of Cook and State of Illinois, have invented certain new and useful Improvements in a Hydrocarbon-Burner; and I do hereby declare that the following is a full, clear, and exact description of the same, reference being had to the accompanying drawings and to the numerals of reference marked thereon, which form a part of this specification.

This invention relates to an improved type of a hydrocarbon gas generating burner wherein downwardly directed burners are disposed to receive an oil-gas from a carbureting chamber and project heating flames against a baffle plate disposed therebelow and below the carbureting chamber to radiate heat for heating a room as well as heating the carbureting chamber to prevent carbonization of the spray nozzle therein, and to assist in the generation of the oil-gas.

It is an object of this invention to construct an oil-gas burner.

Another object of the invention is to provide a portable hydro-carbon burner having an inclosed baffle plate disposed below inverted burners to cause the heating flames to also heat a carbureter to facilitate the generation of an oil-gas fuel.

It is also an object of the invention to provide a hydro-carbon burner in which the carbureter is adapted to be heated by the heating burners disposed therearound and above a baffle plate.

A further object of the invention is the construction of a portable hydro-carbon burner wherein the carbureter and the burners are disposed within a casing above a valve controlled pressure oil tank.

It is furthermore an object of this invention to provide a burner adapted to burn an oil-gas fuel supplied to inverted burners from a carbureter which is heated from the burner flames directed against a baffle plate through which the air and oil supply pipes project.

It is an important object of this invention to provide a hydro-carbon burner of simple and effective construction, having the oil-gas generating and heating mechanisms disposed axially within a hood above a pressure oil can.

Other and further important objects of

this invention will be apparent from the disclosures in the specification and drawings.

The invention (in a preferred form) is illustrated in the drawings and hereinafter more fully described.

On the drawings:

Figure 1 is an elevational view of a hydro-carbon burner embodying the principles of this invention.

Fig. 2 is an enlarged top plan view thereof taken on line 2—2, of Fig. 1, showing the handle in section.

Fig. 3 is an enlarged central vertical section taken through the hood of the burner and showing the oil-gas generator and burners in elevation mounted above the oil tank.

Fig. 4 is a sectional view taken on line 4—4, of Fig. 3, with the handle omitted.

Fig. 5 is a section taken on line 5—5, of Fig. 3.

Fig. 6 is an enlarged fragmentary central vertical section taken through the upper portion of the carbureter and burner devices, with parts broken away and with parts omitted.

Fig. 7 is a bottom plan view of the oil-gas burners.

Fig. 8 is an enlarged end elevation of the carbureter showing the door in open position to permit cleaning of the interior of the carbureter.

As shown on the drawings:—

The reference numeral 1, indicates an oil tank, reservoir or can which also serves as the base of the hydro-carbon stove. Removably threaded into a port provided for the purpose in the upper portion of one side of the can 1, is a knurled passaged plug 2, having a knurled air valve device 3, of any suitable type adjustably engaged therein and adapted to be adjusted to permit air to be pumped into the oil can when the air valve is open and has an air pump attached thereto. The pressure oil can 1, is provided at its top with an integral centrally apertured cylindrical top or cap 4, which projects upwardly above the can to afford a means whereby the lower reduced end of an upwardly flaring neck, collar or funnel flue 5, is securely soldered, brazed or otherwise rigidly secured. The funnel flue 5, is provided with a circumferential row of ventilating openings or apertures 6, arranged around the upper portion of the flue, above a horizontal circular partition or plate 7,

having a central opening 8, and a larger side opening 9, therein for a purpose hereinafter described. The upper margin of the flue 5, is bent outwardly and upwardly to afford a seat 10, and a vertical retaining rim or ring 11.

Projecting through the opening in the cap 4, and axially into the can 1, is a vertical feed or supply pipe 12, which has connected therein directly above the cap 4, a fluid controlling valve 13, equipped with a stem or actuating rod 14. The valve stem 14, projects through an opening in the funnel flue 5, and has an actuating knob or handle 15, secured on the outer end thereof. The feed pipe 12, projects upwardly through the central opening 8, in the partition plate 7, and has removably threaded or otherwise secured on the upper end thereof a nut, head or nozzle 16, having a small spray passage 17, formed on the externally threaded reduced upper closed end thereof. Threaded upon the reduced portion of the nozzle 16, is a horizontally disposed mixing box or carbureter 18, provided at one end with an opening 19, to permit cleaning of the carbureter. Pivotaly mounted on the open end of the carbureter is a shutter or door 20, provided with an integral lug or handle extension 21, to permit actuation of said shutter. The spray passage 17, communicates with the mixing or carbureting chamber 22, of the carbureter 18.

Threaded into an opening in the bottom 35 of the carbureter 18, is the upper end of a vertical air supply tube or pipe 23, the lower open end of which projects through the opening 9, in the partition plate 7. Air is supplied to the lower end of the air tube 23, through an air intake opening 24, formed in the funnel flue 5, below the partition plate 7.

Adjustably engaged on the air supply tube 23, is a support or bracket embracing a cylindrical collar 25, provided with a plurality of integral radial arms 26, the upper flat surfaces of which are flush with the upper end of the collar 25. The bracket 25—26, is adapted to be removably secured in an adjusted position upon the tube 23, by means of a set screw 27, which threads through the collar 25, and engages the tube 23. Seated upon the support 25—26, and vertically adjustable therewith is a circular metal baffle plate or disk 28, having openings 29 and 30, therein through which the pipe 12, and the tube 23, respectively project. Formed integrally upon the upper surface of the baffle plate 28, a short distance to the inside 50 of the periphery thereof, is a circular bead or ridge 31.

A threaded opening is provided in the top wall of the carbureter directly above the nozzle 16, and threaded into said opening is the lower end of a vertical gas pipe 32.

Secured upon the upper end of the gas pipe 32, is a burner holder comprising a chambered three way union or housing 33, having integrally formed thereon three downwardly directed curved arms or elbows 34, which 70 communicate with the interior of the stand pipe 32, through the chamber within the union 33. Secured in the outer end of each of the elbows 34, is the upper end of a vertical burner tube 35, across the lower end of 75 which a burner screen 36, is held by means of a burner member or ring 37. The three burners are directed downwardly and are spaced equidistantly from one another. Said burners are disposed above the baffle plate 80 28, to direct hot oil-gas flames thereagainst to cause heating of said baffle plate to a high temperature to heat the air surrounding the baffle plate, and also the oil supply pipe 12, and the carbureter 18, to volatilize the oil 85 therein to facilitate the generation of an oil-gas fuel.

As clearly shown in Figs. 1 and 3, the oil-gas generating devices of the stove are inclosed by a cylindrical outer casing 38, open 90 at both ends, and having the lower end thereof resting on the seat 10, at the inside of the retaining rim 11. The stove casing 38, is provided with a circumferential row of spaced draft openings 39, a short distance 95 from each end of the casing. Engaged in diametrically opposite apertures provided near the upper portion of the stove casing 38, are the hooked ends of a handle 40, whereby the hydro-carbon stove may be conveniently carried. The supply pipe 12, is rigidly secured to the fuel can 1. Threaded or otherwise secured in the top of the union 33, is a threaded upwardly projecting connector or nipple 41, adapted to removably 100 receive a nut cap 42, threaded thereon to securely hold a stove top or cover 43, locked upon the upper end of the casing 38, to close the same. The stove cover 43, is provided with a downwardly curved circumferential 110 apron or flange 44. A plurality of apertures or openings 45, are provided in the top of the cover 43, to permit escape of the hot air from the interior of the stove casing 38. The nut cap 42, serves to hold the stove 115 parts locked together to permit movement of the stove as a whole. Rigidly formed on the top of the cover 43, are a plurality of projections or knobs 47, affording rests upon which a cooking utensil may be placed if 120 desired.

The operation is as follows:

With the portable hydro-carbon heating stove assembled as shown in Fig. 3, kerosene, gasolene or any other suitable hydro-carbon 125 oil may be admitted into the fuel can 1, by removing the plug 2, and the air valve 3, associated therewith. After again inserting the plug 2, in position, and with the fuel valve 13, closed, air is pumped into the fuel 130

can 1, by means of any suitable kind of air pump the end of which may be engaged in an opening for the purpose provided in the air valve 3, which of course is arranged to 5 be adjusted to permit air from the pump to be forced into the fuel can to exert a pressure upon the oil therein.

To start the operation of the stove the fuel valve 13, is opened by turning the valve 10 stem 14, thus permitting oil from the can 1, to be forced under pressure, upwardly through the supply pipe 12, and into the carbureting chamber 22, through the passage 15 17, in the spray nozzle 16. As clearly shown in Fig. 3, the lower air intake end of the air tube 23, is disposed at a considerable distance below the carbureter 18, so that a sufficient draft is afforded through the tube 23, and in the carbureting chamber 22, to 20 cause the air passing through the carbureter to be carbureted with the oil sprayed from the nozzle passage 17, to form an oil-gas which rises in the pipe 32, and then passes through the elbows 34 and out through the 25 burners. The escaping oil-gas from the downwardly directed burners is ignited by applying a flame through an enlarged opening 46, in the flue 5, and produces a very hot blue flame which strikes against the vertically adjustable baffle plate 28, to heat the 30 same to a high temperature and thus heat the air circulating through the stove due to the arrangement of the air openings 6, 39 and 45. The flames from the burners striking the baffle plate are directed upwardly to cause heating of all of the air passing upwardly around the baffle plate.

The heat from the flames also causes heating of the oil supply pipe 12, and the carbureter 18, thereby causing rapid volatilization of the oil to facilitate carburetion of the air passing through the carbureter to generate the necessary oil-gas fuel for consumption in the stove burners. Heating of the carbureting parts acts to prevent carbonization thereof. In case the carbureter becomes clogged or dirty the same may be cleaned through the opening 19, by opening the shutter 20. Access to the oil-gas generator 45 50 mechanisms is readily had by simply removing the nut cap 42, thereby permitting removal of the stove cover 43, and the stove casing 38. Adjustment of the baffle plate 28, is permitted by releasing the set screw 27, 55 which holds the baffle plate bracket in position on the air tube 23.

The heated air from the stove escapes from the openings 45, in the stove cover 43, to heat the room wherein the stove is placed. 60 Heat is also radiated by the casing 38, and the cover 43. The process of oil-gas generation is stopped by simply closing the oil supply valve 13, and permitting the generated oil-gas to burn out.

65 If desired the stove may be used as a

cooking device by simply using the cover as a burner and placing a cooking utensil upon the supporting knobs 47, for the purpose of heating water or for cooking.

I am aware that numerous details of construction may be varied through a wide range without departing from the principles of this invention, and I therefore do not purpose limiting the patent granted otherwise than necessitated by the prior art 75 and the appended claims.

I claim as my invention:

1. A hydro-carbon burner comprising a fuel tank, oil-gas generating means mounted thereon to receive oil therefrom, said generating means including adjustable heating means, said generating means being provided with a removable plate.

2. A hydro-carbon burner embracing a pressure fuel tank, a carbureter mounted thereon to receive oil therefrom, a removable plate on the end of the carbureter, means for supplying air to the carbureter to be mixed with the oil to form an oil-gas, and burner members connected with said carbureter adapted to burn the generated oil-gas as a fuel for heating purposes.

3. A hydro-carbon burner comprising a pressure oil can, oil-gas generating devices supported thereon to receive oil under pressure therefrom, said generating devices including adjustable heating means and means for inclosing said oil-gas generating devices.

4. An oil-gas generator embracing carbureting means, oil and air supply pipes connected therewith, inverted burners supported on said carbureting means adapted to burn the oil-gas generated therein, and baffle means adjustably mounted on one of said supply pipes below said burners to be heated by the flames escaping therefrom.

5. An oil-gas generator comprising a carbureter, means supporting the same adapted to supply oil thereto under pressure, an air supply tube connected with said carbureter to supply air thereto for mixing with the oil therein to form an oil-gas fuel, inverted burners supported by said carbureter to receive the oil-gas therefrom, a baffle plate below said burners and carbureter, and means adjustably engaged on said air supply tube for holding said baffle plate in an adjusted position.

6. The combination with an oil-gas generator and burner, of baffle means adjustably mounted thereon adapted to be heated thereby to act both as a generating means and to radiate the heat received, and apertured closure means for said oil-gas generator and burner, and for said baffle means.

7. The combination with an oil-gas generator and burner device, of baffle means adjustably mounted thereon for radiating the heat received therefrom, and a carbureter

mounted above the baffle means, said carbureter being provided with a removable cover.

8. An oil-gas generator comprising a vertical oil supply pipe, a carbureter mounted on the upper end thereof, an apertured baffle plate below said carbureter through which said oil pipe projects, a vertical air supply tube connected to said carbureter and projecting downwardly through said baffle plate, a bracket adjustably mounted on said air tube for supporting the baffle plate, a gas pipe mounted on the carbureter to receive the oil-gas therefrom, a union on said gas pipe, a plurality of downwardly directed elbows connected therewith, and a burner attached to the lower end of each of said elbows to direct flames against the baffle plate.

9. An oil-gas generator comprising a plurality of downwardly directed burners, a baffle plate adjustably mounted therebelow,

said baffle plate acting in combination with a carbureting means for generating an oil-gas and supplying the same to said burners, and adapted to receive and radiate the heat produced by the flames from said burners.

10. A hydro-carbon burner comprising a pressure fuel tank, a carbureter mounted thereon to receive oil therefrom, adjustable heating means on the carbureter, means for supplying air to the carbureter to be mixed with the oil to form an oil-gas, and burner means connected with said carbureter adapted to burn the generated oil-gas.

In testimony whereof I have hereunto 35 subscribed my name in the presence of two subscribing witnesses.

JAY F. LAWRENCE.
